Turney H. Stough, Jeannette, Pa.

Application August 17, 1945, Serial No. 121,449

Term of patent 7 years

(Cl. D58—9)

To all whom it may concern:

Be it known that I, Turney H. Stough, a citizen of the United States, residing at Jeannette, in the county of Westmoreland and State of Pennsylvania, have invented a new, original, and ornamental Design for a Candy Containing Toy Telephone, of which the following is a specification, reference being had to the accompanying drawing, forming part thereof.

In the drawing:

I claim:

The ornamental design for a candy containing toy telephone, as shown.

TURNEY H. STOUGH.
